UNITED STATES PATENT OFFICE.

FRANK E. SAECKER, OF APPLETON, WISCONSIN, ASSIGNOR TO APPLETON MACHINE COMPANY, OF APPLETON, WISCONSIN.

SHAFT-CO尤LING.

1,137,290.

Specification of Letters Patent. Patented Apr. 27, 1915.

Application filed September 2, 1913. Serial No. 737,561.

To all whom it may concern:

Be it known that I, FRANK E. SAECKER, a citizen of the United States, and resident of Appleton, in the county of Outagamie and State of Wisconsin, have invented certain new and useful Improvements in Shaft-Couplings; and I do hereby declare that the following is a full, clear, and exact description thereof.

10 My invention refers to paper refining engines, one object being to provide a simple, economical and effective means for coupling the shaft of a prime mover, of the electric motor type, to the plug-shaft of the refining engine, whereby a certain amount of play is permitted between the shafts, there being means in connection with the coupling for absorbing shock incidental to vibration of the connected devices.

20 Another object of my invention, in addition to the yieldable coupling means, is to provide an indirect gear connection between the engine plug-shaft and the casing of the motor-shaft, whereby said motor and plug-shaft are synchronously adjusted to maintain their relative positions co-incident to adjustment of the engine plug in its shell, the aligned shafts being moved thus independently.

30 With the above objects in view the invention consists in certain peculiarities of construction and combination of parts as hereinafter set forth with reference to the accompanying drawings and subsequently claimed.

35 In the drawings Figure 1 represents a side elevation of a paper refining engine of the "Jordan" type and an electric motor for driving the same, the shaft of the motor and engine being connected by a yieldable coupling with certain parts of the device broken away and in section to more clearly illustrate structural features; Fig. 2, a detailed cross-section upon an enlarged scale of the coupling members, the section being indicated by line 4—4 of Fig. 1; Fig. 3, a detailed longitudinal sectional view of the coupling members showing the same attached to fragments of their respective shafts, the section being indicated by line 5—5 of Fig. 2, and Fig. 4, a detailed perspective view of one half of one of said coupling members, it being understood that two of such members, as shown, are connected together to constitute 55 a single coupling member.

Referring by characters to the drawings, 1. indicates the tapered shell of a refining engine, the same being supported upon a bed 1' by suitable interposed blocks. 2 and 2' represent brackets extending 60 from the discharge and feed end respectively of the shell, which brackets support boxes 3, 3', into which is journaled a plug-shaft 4. The feed end box 3' is rigidly secured to the bracket 2', while the discharge end box 3 is 65 slidably mounted upon the bracket 2 and is provided with annular rings which engage annular recesses in the plug-shaft whereby said plug-shaft is longitudinally shifted coincident to a corresponding shift of the box, 70 it being understood that the plug-shaft moves endwise through the feed end box 3'. Secured to the shaft 4 is the ordinary plug 5 which is revolubly mounted within the shell and adapted to be moved endwise with 75 the shaft, whereby variations in the cut is effected. The journal box 3 is provided with a depending ear, which ear is in threaded union with a screw 6, the said shaft being revoluble in the ear 7 that constitutes part 80 of the bracket 2. This screw is provided at its end with a hand-wheel 7' and also a sprocket-wheel 8, which sprocket-wheel is connected by a link-belt to a corresponding sprocket-wheel 8' that is mounted upon one 85 end of a spindle 9. The said spindle is journaled at its sprocket-carrying end in a hanger 10 that extends from the adjacent end of the bed 1'. The opposite end of the spindle 9 has secured thereto a threaded section 9', which section, in turn, is in threaded union with the boss 11, the same being rigidly connected by a web 11' to the base-plate 12 of a motor-casing 13, as best shown in Fig. 1. The base-plate of the motor-casing 95 is supported upon longitudinal series of anti-friction rollers 14, which rollers are mounted in suitable bearings of troughs 15 that are separated transversely into oil pockets, whereby the gangs of rollers which support the base are suitably lubricated, the said base-plate being also guided by rails 16 which overlap the upper faces of the base and are secured to flanges of the bed-plate. 100

105 Mounted in suitable journals with which the motor-casing is provided is a motor-shaft 17, which shaft is axially aligned with the plug-shaft 4, the said motor-shaft constituting a drive-member for the latter.

110 The motor-shaft 17 has secured thereto a

coupling member A and the juxtaposed end of the plug-shaft a corresponding coupling member B. These coupling members are similar in construction and are each formed in separable halves 18, 18', which halves are divided longitudinally and are clamped to their respective shafts by bolts 19, the said coupling members being held against rotation upon the shaft ends by a spline connection. Each half of the coupling member A is provided with a tongue-and-grooved projecting head 20 in the form of a sector approximating one quarter of a circle, the coupling member B which is secured to the plug-shaft being provided with similar tongue-and-grooved heads 21, the pairs of the opposing heads being interlocked to effect a coupling engagement between the shafts. The stepped faces of the heads or sectors, constituting the tongue-and-grooves, are, as best shown in Fig. 2, spaced apart for the reception of tapered yieldable wedge-blocks 22, there being two of such wedge-blocks in connection with each joint, the same being interposed between the groove of one sector and the tongue of the opposing sector. These wedge-blocks are preferably composed of rubber or other yieldable material and are held in their seats by means of a confining ring 23, which ring is fitted over the circular faces of the heads.

From the foregoing description it is apparent that when the plug-shaft, together with the plug, are adjusted by means of manually rotating the screw 6, the gear connection between said worm-shaft and the spindle 7 will cause movement of the motor-shaft in synchrony with movement of said plug-shaft, due to the threaded union between the spindle section 9' and boss 11 that projects from the base-plate of the motor-casing, whereby said motor-casing is shifted back or forth upon its supporting rollers. It is also apparent from the foregoing description with reference to the yieldable coupling connection between the drive and driven shafts that vibration co-incident to high speed of the motor-shaft will be absorbed as power is transmitted to the driven plug-shaft due to the interlocked coupling members with which the ends of the juxtaposed shafts are provided, there being a

slight yield between the coupling connections caused through the interposed blocks 22. Thus it is apparent that the shock absorbing coupling connection will cause motion to be imparted from the motor to the refining engine without impairing the efficiency of the device and should the shafts become slightly displaced with relation to 60 alignment grinding or wear will not result due to the compensating movement of said coupling members.

I claim:

1. A coupling connection comprising a 65 pair of shafts each having a halved coupling member secured thereto, each half of the coupling member being provided with a tongue-and-grooved sector for interlocking engagement with the tongue-and-grooved 70 sectors of the opposite coupling member, and shock-absorbing plugs fitted between the engaging faces of the tongue-and-groove sectors.

2. A coupling connection comprising a 75 pair of aligned shafts, a coupling member secured to each shaft each member being halved, means for clamping the halves together, a tongue-and-grooved sector extending from each half for interlocked engagement with the sectors of the opposite member, the interlocking joints being spaced apart, and shock absorbing plugs fitted within the spaces between said sectors.

3. A coupling means for aligned shafts 85 comprising pairs of longitudinally halved coupling members, each pair being provided with companion male and female tongue-and-grooved sectors for interlocking engagement with the corresponding tongue-and-grooved sectors of the opposite coupling member, and means for securing the halves of each coupling member together, the said coupling members being halved to intersect their respective female sectors.

In testimony that I claim the foregoing I have hereunto set my hand at Appleton in the county of Outagamie and State of Wisconsin in the presence of two witnesses.

FRANK E. SAECKER.
